UNITED STATES PATENT OFFICE.

JOSEPH GUMBER, PAUL GUMBER, AND JOHN HARDER, OF EAST MOLINE, ILLINOIS.

ROLLING SCREEN.

1,242,177.

Specification of Letters Patent.

Patented Oct. 9, 1917.

Application filed February 21, 1917. Serial No. 150,182.

To all whom it may concern:

Be it known that we, JOSEPH GUMBER, PAUL GUMBER, and JOHN HARDER, citizens of the United States, residing at East Moline, in the county of Rock Island and State of Illinois, have invented certain new and useful Improvements in Rolling Screens, of which the following is a specification, reference being had to the accompanying drawings.

This invention relates to an improved rolling screen for windows, porches, and like places where it is desirable to completely screen the opening to prevent the entrance of flies and other insects, and also permit of the easy and quick removal of the screen from the opening, when desired.

It is the principal object of the present invention to provide certain improvements in a screen of the above type as disclosed in our prior application for patent, filed March 27, 1916, Serial No. 87,015.

One feature of improvement embodied in the present invention, resides in the provision of means for mounting the screen roller for bodily oscillating movement upon the window frame or other supporting structure as the screen is withdrawn or lowered or rolled upon the roller.

It is another object of the invention to devise improved means whereby the screen roller and its casing may be easily and quickly mounted upon or removed from the ordinary window structure, and to provide means which will prevent the frictional binding engagement of the roller or the screen material with the casing or the window frame.

The invention has for another important object to provide improved means for detachably connecting the screen material at one of its ends to the roller, and means for attaching a metal strip to the other end edge of the screen whereby the screen may be conveniently raised or lowered, and automatically acting means to momentarily hold the screen in its lowered position and prevent rolling of the same under the action of the roller spring while said metal strip is being suitably fastened to the window sill or other stationary part.

It is a further general object of our present invention to provide improvements of the character above noted in our original device, which will greatly increase the serviceability and utility of the invention disclosed in our prior application, but without materially increasing the manufacturing cost thereof.

With the above and other objects in view, our invention consists in the novel features of construction, combination and arrangement of parts to be hereinafter more fully described, claimed and illustrated in the accompanying drawings, in which,

Fig. 1 is a vertical sectional view illustrating our improved screen applied to a window;

Fig. 2 is a front elevation, the screen roller being shown in section;

Fig. 3 is an enlarged section taken on the line 3—3 of Fig. 2;

Fig. 4 is a fragmentary elevation of one end of the roller frame, showing the means for detachably mounting the same upon the window casing;

Fig. 5 is a vertical sectional view through the lower end of the screen guide showing the means for automatically locking or holding the screen in its lowered position;

Fig. 6 is a section taken on the line 6—6 of Fig. 5;

Fig. 7 is a transverse section taken on the line 7—7 of Fig. 5;

Fig. 8 is a vertical section of the upper portion of the window frame;

Fig. 9 is an enlarged sectional view showing a slightly different connecting means between the upper end of the screen fabric and the rope; and

Fig. 10 is a detail sectional view through one end of the flexible screen.

Referring in detail to the drawings, F indicates a window frame, S the sill, and S' the outer sash. C indicates the outer stop bar or cleat which retains the sash in place, and H the head rail or bar upon which the frame is secured. It will be understood that the illustration of the window frame is purely conventional and the invention which we will now proceed to describe in detail is applicable to various other frame structures.

In one embodiment of our invention which is most clearly illustrated in Fig. 1 of the drawings, there is provided a casing generally designated by the numeral 5 and 5 preferably constructed of sheet metal. This casing includes a rear wall 6, a top wall 7, and end walls 8. The front or outer side of this casing is open and the top wall 7 thereof is adapted to extend under and in contact 10 with the edge of the head bar H while the rear wall 6 is in abutting contact with the outer edge of the stop or cleat C.

For the purpose of conveniently mounting 15 this casing and the screen roller and associated parts which are carried thereby in its operative position upon the window frame, slide plates 9 are employed, said wall being provided with outwardly struck, spaced guide lugs 10 engaged over the longitudinal edges of the slide plates. This plate which is preferably of sheet metal, is 20 centrally formed with a longitudinally extending, reinforcing rib 11. The ends of the plate 9 are angularly bent, as shown at 12, 25 and the end 12 of the slide plate nearest the end of the casing is provided with an opening 13 therein. Supporting pins 14 are driven through the cleats C and into the side bar of the window frame. In mounting 30 the screen roller and casing in place, it will be understood that the slide plates 9 are first drawn inwardly so that the outer angular ends 12 thereof will project inwardly from the pins 14. By now shifting 35 the slide plates outwardly, the pins 14 are received in the openings 13. These pins 14 are preferably slightly tapered so that they will bind against the edges of the openings 13. Thus, the screen roller and casing will be 40 securely retained in their applied positions.

The screen roller is in the form of a hollow, metal cylinder 15, and within this cylinder a relatively stationary, center rod 16 is arranged. The cylinder is provided in its 45 opposite ends with the bearings 17 soldered or otherwise securely fixed to the cylinder wall and each having a central opening through which the rod 16 is loosely engaged. An additional bearing 18 in the form of a 50 spider is also arranged centrally within the tubular roller 15 and has the outer ends of its arms angularly bent for frictional engagement with the wall of the roller. The extremities of the rod 16 which project beyond 55 the end bearings 17 in the roller are fixed in the circular, dished ends 19 of the arms 20. These arms are mounted eccentrically with relation to the rod 16 upon the fixed pivot studs 21 suitably secured in the 60 end walls 8 of the roller casing, and the outward swinging movement of said arms is limited by lugs 20' projecting inwardly from the end walls of the case 5.

To one of the end bearings 17 of the screen

roller, an inwardly projecting sleeve 22 is 65 rigidly fixed at one end, preferably by means of lugs 23 which extend through openings in the bearing plate and are clenched upon the opposite side of the plate. A wood roller 24 is centrally bored to tightly fit 70 upon the rod 16, one end of said roller being engaged within the collar 22 and said end of the roller being preferably recessed to receive a central hub flange 17' on the bearing plate 17. A metal cap or sleeve 25 is engaged over the opposite end of the wood roller 24 and has an arm 26 struck out of its annular wall and extending radially from the end of the cap. This cap is securely pinned or otherwise fixed to the 80 roller 24 and the rod 16. 27 designates the screen roller spring which extends the entire length of the wood roller 24 and, at its ends, fits snugly upon the sleeve 22 and cap 25. One terminal of this spring is engaged 85 through an opening in the arm 26 on the cap 25 and the other terminal thereof suitably secured to the sleeve 22.

A sheet metal roller 15 has a longitudinally extending, rectangular channel 28 90 formed therein by pressing the metal inwardly. The wire screen fabric 29 has each of its ends secured in a reversely bent, ductile metal strip 30 extending the entire width of the screen. The parallel parts of these metal strips are tightly clenched together and thus securely fixed to the edges of the screen fabric without necessitating the use of other fastening elements. The clenched metal strip 30 on the upper end of the screen fabric is adapted to be forced into the rectangular channel 28 of the screen roller under pressure, so that the side walls of the channel will clampingly and frictionally engage the metal strip and retain the same in 100 connection with the roller against all possibility of its casual displacement or disconnection therefrom.

To the opposite sides of the window frame and immediately adjacent the outer edge of the stop cleat C, the guides 31 are secured. These guides, as shown more clearly in Fig. 7 of the drawings, each consists of a sheet metal strip bent upon itself to provide a hollow, rectangular casing 32 and a flange 33 115 extending longitudinally of the casing and projecting laterally therefrom, constituting practically a continuation of one of the casing walls. The longitudinal edges of the metal plate from which the guide is formed are spaced apart to provide a slot or opening 34 in the opposed wall of the casing. The flange 33 which is produced at the central fold in the metal plate and is, therefore, of double thickness, is provided with suitable 120 openings to receive fastening screws 35 whereby the guide may be securely fixed to the window frame. The vertical edges of

the screen fabric 29 are movable in the slots 34 and project within the hollow guide casings 32.

For the purpose of conveniently raising and lowering the screen, we provide a metal plate which is bent upon itself to provide a longitudinally extending channel 36 therein, said channel being adapted to receive the reinforcing metal strip 30 clenched upon the lower edge of the screen fabric. One edge of the metal plate is extended upwardly in parallel relation to one of the side walls of the channel 36, as indicated at 37, and provides a bearing or contacting surface for the screen fabric. The other edge of the metal plate is laterally extended to afford a flange 38 which is slotted at spaced points to receive turn buttons or other suitable fastening means 39 on the window sill S.

For the purpose of holding the screen fabric 29 in its lower position while the flange 38 of the channel plate is being fastened to the window sill, we have provided a metal bar 40 in each of the rectangular guide casings 32, which extends substantially the entire length thereof. This metal bar is vertically movable between the inner side wall of the casing 32 and spaced tongues 30 or lugs 41 which are struck from the rear wall of the casing and angularly bent and disposed in parallel relation to said bar. The inner side wall of the casing 32 is bent or projected inwardly at spaced points to provide sloping or inclined shoulders 42. The metal bar 40 has spaced recesses 43 in one of its longitudinal edges and is longitudinally slit in one direction from each of these recesses, as at 44, to provide resilient or spring arms 45. The free end of each of these spring arms, at its outer edge, has a single tooth or projection 46 formed thereon. Each of the metal bars 40, at its lower end, has an angularly disposed flange 47 formed thereon which is normally disposed about one-half inch above the sill S. The opposite ends of the flange 37 extend through the slots 34 and into the guide casings 32. It will thus be seen that when the screen is pulled down and unwound from the roller 15, whereby the spring 27 is placed under a gradually increasing tension, the ends of the flange 37 will strike the angular flanges 47 on the lower ends of the vertically movable bars 40. The bars 40 will thus be forced downwardly in the guide casings 32 and the free ends of the spring arms 45 riding upon the bevels or inclines 32 will be forced laterally so that the teeth 46 will engage the screen fabric and hold the same against upward movement under the action of the spring 27, it being understood, of course, that the channel plate 36 is held by the operator and forced downwardly upon the

window sill until it is secured by the fasteners. When the plate 36 is released, the spring 27 tending to unwind pulls the screen fabric upwardly or stretches the same, thereby holding the fabric perfectly taut. As soon as the plate 36 is released, the unwinding of the roller spring 27 pulls the screen fabric upwardly and the bars 40 are returned to their normal positions owing to the engagement of the teeth 46 with the fabric. The spring arms 45 again assume their normal conditions and co-act with the inwardly inclined portions 42 of the guide casings to prevent downward sliding movement of the bars 40. It will thus be seen that the screen will be securely held in its lowered position and excessive strains upon the screen fabric, at its lower end which is attached to the channel plate 36 by the upward pull upon the screen, is to a large extent obviated, and the fasteners for the plate 36 also relieved of excessive pressure.

Upon the end walls 7 of the roller case, a curved shield plate 48 is pivotally mounted as at 48' and extends outwardly over the screen roller, said shield plate being of greater length than the roller and projecting beyond the ends thereof.

Bearing lugs 49 are inwardly struck from the rear wall 6 of the roller case 5, adjacent to the top wall 7 thereof, and wood rolls 50 are mounted between these bearing lugs and the end walls of the case. These rolls limit the swinging movement of the eccentrically mounted roller supports 20 in one direction and prevent frictional engagement of the roller or the screen thereon with the rear wall of the case.

In the operation of the device as above described, it will be understood that the screen fabric 29 is normally wound upon the roller 15. When this fabric is pulled downwardly to cover the window frame opening, the roller 15 is rotated upon the rod 16 and the coil spring 27 is thereby placed under tension. As the screen is unwound from the roller and the tension of the spring increases, the roller is oscillated and moved inwardly into bearing contact with the anti-friction rollers 50. Upon the release of the screen at its lower edge, the spring 27, as it uncoils, reverses the rotation of the roller so that the fabric is wound thereon and the roller and the supports 20 between which it is mounted, swing outwardly toward the shield or cover 48. The shield 48 under the pressure of the accumulated screen fabric against its lower edge, will yield and move upwardly, and as the screen is unwound from the roller, this shield plate, of course, returns to its normal position. The lower edge of the plate 48 is preferably provided with a bead 51 which engages the screen material so as to properly shed rain

water and prevent the same from collecting upon the screen fabric.

In Fig. 8 of the drawings, we have shown a slightly modified mounting and arrangement of the device, wherein the same is disposed interiorly of the bar H of the structure and above the window frame. The pivoted roller supports 20 are mounted upon brackets 52 which are suitably secured to the bar 8 and the top of the window frame. The top bar of the frame is provided with suitable openings in line with the guide casings 32 so that the screen fabric may be drawn downwardly through said guides. 15 Each of the brackets 52 is provided with a suitable bearing support for an anti-friction roller 50' arranged at opposite ends of the screen roller and preventing frictional engagement of the latter with the bar H. The construction of the roller and arrangement of the central rod and the roller spring is identical with that above described, and the device operates in a similar manner. 20 25 In Fig. 9, we have shown another means for connecting the upper edge of the screen fabric to the roller. In this case, a plurality of light, metal straps 53, preferably four in number, are employed, and the ductile reinforcing strip 30' is slotted, as at 54, to receive one end of said strips, the terminal of the strip being tightly secured to the body of the strip by a metal loop 55 which is clenched thereon. The other or upper end 30 of each of these flexible metal straps is inserted through spaced slots or openings 56 in the wall of the sheet metal screen roller, the strap terminals being bent reversely and extended between the body of the strap 35 and the peripheral face of the roller. This means of connecting the screen to the roller is of especial advantage when the device is mounted and arranged as shown in Fig. 40 45 8, as it admits of the easy and quick renewal of the screen fabric without necessitating the dismounting of the screen roller.

From the foregoing description, taken in connection with the accompanying drawings, the construction and advantages of the several features of improvement which we have made in our original invention will be fully understood. It will be appreciated that by means of the improved mounting of the screen roller and the means for fastening or securing the same in lowered position, the practical utility and efficiency of the device in actual use is materially increased. At the same time, however, these improvements are of a very simple character and 50 55 will not add to any great extent to the manufacturing cost of the original device.

While we have herein shown and described what we have found to be a very practical construction and operation, it will

be understood that in applying the invention to various analogous purposes, minor alterations may be required by the circumstances of each particular case. It is, therefore, to be understood that we reserve the privilege of adopting all such legitimate changes in the form, proportion and arrangement of the several elements as may be fairly embodied within the spirit and scope of the invention as claimed.

Having thus fully described our invention, what we desire to claim and secure by Letters Patent is:

1. In combination, a casing open upon one side, a screen roller, means for mounting said roller at its ends for bodily movement with respect to the casing, and relatively stationary means mounted within the casing and co-acting with the roller as the material is wound thereon to urge said roller outwardly from the open side of the casing. 85

2. In combination, a casing open upon one side, a screen roller, means for mounting said roller at its ends for bodily movement with respect to the casing, a spring acting to wind the material upon the roller, and relatively stationary, anti-friction rollers mounted in the casing and co-acting with the roller to urge the same in an outward direction from the open side of the casing as the material is wound thereon. 95

3. In combination, spaced oscillatable supports, a roller rotatably mounted upon said supports, a flexible material connected to said roller, a stop member, a spring acting to rotate the roller in one direction and wind the material thereon, and means co-acting with the roller as the material accumulates upon the same, whereby the roller is caused to swing bodily with the supports, one of the supports engaging said stop member to 100 positively limit such swinging movement. 100

4. In combination, spaced oscillatable supports, a roller rotatably mounted upon said supports, a flexible material connected to said roller, a spring to rotate the roller in one direction and wind the material thereon, a yieldable member extending upon one side of the roller axis, and means co-acting with the roller on the opposite side of its axis and urging the same to its normal position and against the resistance of said yieldable member as the material accumulates upon the roller. 115

5. In combination, spaced oscillatable supports, a roller rotatably mounted upon said supports, a flexible material connected to said roller, a spring to rotate the roller in one direction and wind the material thereon, a yieldable member extending upon one side of the roller axis, and anti-friction members 120 rotatably mounted above the roller axis and on the relatively opposite side thereof and operating to urge the roller to its normal 125

position as the material accumulates upon said roller.

6. The combination with a supporting structure, of a spring actuated roller mounted upon said structure, spaced guides secured to the structure, a flexible material connected to the roller and movable in said guides, means attached to the free end of the flexible material to pull the same from the 10 roller and movable in the guides, and holding devices engaged and actuated by the means on the free end of the flexible material when the same is unwound from the roller, whereby the devices are caused to operatively engage the material and hold the same against reverse movement under the action of the roller spring.

7. The combination with a supporting structure, of a spring-actuated roller mounted upon said structure, a flexible material connected at one of its ends to said roller, spaced hollow guides fixed to the structure in which the opposite edges of the screen are engaged, a holding device movably mounted in each of the hollow guides, and means on the free end of the material movable in said guides and adapted to engage the holding devices when the material is withdrawn from the roller, whereby said devices are caused to engage and hold the screen against reverse movement under the action of the roller spring.

8. The combination with a supporting structure, of a spring-actuated roller mounted thereon, tubular guide members fixed to the supporting structure at the opposite ends of the roller, a flexible material connected at one end to the roller and having its opposite edges movably engaged in said guide members, spaced parts longitudinally movable within each of the guide members and adapted to co-act with one wall of the guide member when moved in one direction, whereby said parts are projected into engagement with the edges of the screen to hold the same against reverse movement under the action of the roller spring, and means fixed to the flexible material and movable in said guides to move said parts and cause the same to operatively engage the flexible material.

9. The combination with a supporting structure, of a spring actuated roller mounted thereon, tubular guides fixed to the structure at opposite ends of the roller, a flexible material connected at one of its ends to the roller and having its opposite edges engaged in said guides, a vertically movable bar mounted within each of the guides and having spaced, resilient arms each provided with a tooth at its free end, one wall of the tubular guide being provided with spaced projections with which the respective arms engage in the movement of the bar in one direction to urge the teeth on said arms into

engagement with the edge of the flexible material, whereby the same is held against movement under the action of the roller spring, and means secured to the free end of the flexible material and movable in said guides to actuate said bars when the material is withdrawn from the roller.

10. In combination, a casing open upon one side, oscillatable supports mounted upon the end walls of the casing, a roller rotatably mounted upon said supports for bodily movement therewith, a yieldable shield plate extending downwardly from the top wall of the casing over the open side thereof to confine the roller within the casing, a flexible material connected to said roller, a spring acting to rotate the roller in one direction and wind the material thereon, and anti-friction members rotatably mounted in the opposite ends of the casing above the axis of the roller and co-acting with the roller to prevent binding contact of the same with the casing wall when the material is unwound from the roller, said members operating to urge the roller toward and in contact with the yieldable shield plate as the material accumulates thereon.

11. The combination with a supporting structure, of a casing, supporting pins fixed in said structure, longitudinally movable slide plates mounted upon the opposite ends of the casing, each of said plates having an angular, laterally projecting end portion provided with an opening adapted to receive one of said pins when the plate is shifted in one direction on the casing wall to detachably sustain the casing upon said pins, and a spring actuated screen roller mounted in said casing.

12. In combination, a casing upon one side, bodily movable supports mounted within said casing, a screen roller carried by said supports and projecting from the open side of the casing, means within the casing to limit the bodily movement of the screen roller in one direction, and means limiting the movement of said roller in an outward direction from the open side of the casing when the material is wound thereon.

13. In combination, a casing, oscillatable supports mounted upon the end walls of the casing, stop lugs projecting from the casing walls and limiting the movement of the supports in one direction, a screen roller rotatably mounted in the supports, and means to co-act with the roller and prevent frictional contact of the same with the wall of the casing in the swinging movement of the supports as the screen is withdrawn from the roller.

14. In combination, a casing, oscillatable supports mounted upon the end walls of the casing, stop lugs on the end walls of the casing limiting the movement of the supports

in one direction, a spring actuated roller rotatably mounted upon said supports, a guard plate pivotally mounted upon the end walls of the casing and extending outwardly over
5 the roller, the free longitudinal edge of the guard plate contacting with the roller, and means limiting the swinging movement of the supports in an opposite direction to prevent frictional contact of the roller with the
10 casing wall when the material is withdrawn from the roller.

In testimony whereof we hereunto affix our signatures in the presence of witnesses.
